UNITED STATES PATENT OFFICE

PETER H. MEYER, OF BUFFALO, NEW YORK

DESIGN FOR A VASE

Application filed November 15, 1930. Serial No. 37,671. Term of patent 7 years.

To all whom it may concern:

Be it known that I, PETER H. MEYER, a citizen of the United States, residing at Buffalo, in the county of Erie and State of New York, have invented a new, original, and ornamental Design for Vases, of which the following is a specification, reference being had to the accompanying drawing, forming a part thereof.

The plain portion in Fig. 1 between the lower part of the L-shaped portion of the vase and the remainder of the vase represents open spaces.

I claim:

The ornamental design for a vase, as shown and described.

PETER H. MEYER.
